(21) Appl. No.: **29/328,539**

(57) **CLAIM**

(22) Filed: **Nov. 25, 2008**

The ornamental design for a fan cage for a barbecue blower attachment, as shown and described.

(51) **LOC (9) Cl.** **23-04**

DESCRIPTION

(52) **U.S. Cl.** **D23/412**

FIG. 1 is a top perspective view of a fan cage for a barbecue blower attachment showing our new design;

(58) **Field of Classification Search** D23/412,

FIG. 2 is a front elevational view thereof;

D23/411, 382, 381, 332; 416/244 R, 247 R;

417/411

See application file for complete search history.

FIG. 3 is a left side elevational view thereof, the right side being a mirror image;

(56) **References Cited**

FIG. 4 is a rear elevational view thereof;

U.S. PATENT DOCUMENTS

FIG. 5 is a top plan view thereof; and,

2,017,431 A 10/1935 Anderson et al.

FIG. 6 is a bottom plan view thereof.

3,697,198 A * 10/1972 Holder, Jr. 417/411

The broken lines showing the fan blade, neck, and fan motor housing of the blower attachment are for the purpose of illustrating environmental structure and form no part of the claimed design.
